UNITED STATES PATENT OFFICE.

PAUL SHANNON, OF NORWICH, CONNECTICUT.

TENSION DEVICE FOR SHUTTLES.

Application filed December 18, 1923. Serial No. 681,392.

To all whom it may concern:

Be it known that I, PAUL SHANNON, a citizen of the United States, and a resident of Norwich, in the county of New London 5 and State of Connecticut, have invented a new and Improved Tension Device for Shuttles, of which the following is a full, clear, and exact description.

This invention relates to improvements in 10 shuttles for looms, and has particular reference to a tension device therefor.

In tension devices for looms it is customary to employ a movable tensioning member and cooperating stationary guide members, 15 such as pins, about which the thread is alternately passed, the movement of the first-named member being utilized to maintain the thread under proper tension as the shuttle is operated. The operation of threading 20 these devices is oftentimes a tedious and difficult one owing to the relative arrangement of the parts.

An object of the present invention is to provide an improved tension device which 25 is so constructed as to facilitate the threading thereof.

Another object is to utilize the movement 30 of the movable tensioning member from its normal position to engage the thread with the stationary guide members when the device is being threaded so that said thread will pass alternately or back and forth from various portions of the movable member to each of the guide members.

35 The above and other objects will appear more clearly from the following detailed description when taken in connection with the accompanying drawing which illustrates a preferred embodiment of the inventive 40 idea.

In the drawing—

Figure 1 is a plan view of the shuttle constructed in accordance with the invention;

45 Figure 2 is a fragmentary longitudinal section on the line 2—2 of Figure 3;

Figure 3 is a similar view on the line 3—3 of Figure 1;

Figure 4 is a transverse section on the line 4—4 of Figure 3; and

50 Figure 5 is a similar view on the line 5—5 of Figure 3.

The shuttle 6 is constructed in a manner well known in the art and provided with means for properly positioning the bobbin 55

7. Adjacent one end of the shuttle the same is provided with a recess for receiving the

casing 8 of the tensioning device which includes the essential features of the present invention.

The movable tensioning member forming 60 a part of the tension device is generally indicated by the numeral 9 and is formed of a single length of wire or other suitable material which is bent at one end to provide a helical coil 10 which is mounted upon a pivot pin 11 when the member is in its operative position. The extremity of the wire adjacent the coil has connected thereto one 65 end of a suitable elastic member 12, the other end of which is secured in the shuttle 70 as at 13, and said member 12 operates to yieldingly maintain the member 9 in the normal full-line position shown in Figure 2. The portion of the wire forming the 75 member 9 adjacent the end thereof opposite the coil 10 is bent to provide a series of guide loops 14 each of which is offset with respect to the next adjacent loops so that 80 said loops will be arranged in staggered relation to form a channel through which the thread 15 may be extended. Each loop may be bent outwardly, as best indicated at 16, (Figure 4) so as to facilitate the introduction of the thread into the channel 85 formed by said loops when the tension device is being threaded. When the member 9 is in its normal position, as shown in full lines in Figures 4 and 5, the bent portions 16 of the loops are arranged outwardly beyond the turndown guide extensions 17 of 90 the casing 8. Thus when a thread is being introduced into the casing the same may be engaged with said extensions 17 which will guide the same into the loops 14, as illustrated in Figure 4, the thread being forced 95 to the inner or lower ends of the loops.

Cooperating with the movable member 9 are a plurality of stationary guides 18 supported upon the base of the casing 8 and positioned so as not to interfere with the 100 loops 14 of the member 9 when the latter is moved about its pivot 11 when the shuttle is being operated. The guides 18 are of successively increasing size from the inner guide which is next adjacent the pivot end 105 of the member 9 so that the effective ends of said guides with which the thread is brought into engagement are arranged on a line extending diagonally with respect to the longitudinal axis of the tension device. 110 This construction is clearly shown in Figure 2. Each guide 18 is provided with an in-

clined edge 19 arranged in such manner that after the thread 15 has been introduced into the loops 14 and the member 9 is swung about its pivot to the dotted-line position shown in Figures 2 and 4, the thread 15 will engage said inclined edges and thereby be guided over the guides 18, after which the thread will assume the position, as indicated in Figure 4. Upon the restoration of the member 9 to its normal position the thread will then be alternately engaged with the loops 14 and guides 18, as shown in Figure 2. It will thus be apparent that the invention provides an effective means for quickly threading the tension device, the parts of which will at all times maintain the thread under tension during the operation of the shuttle. In order that any danger of the thread being engaged with the coils 10 during the operation of the shuttle will be obviated a pin 20 is arranged adjacent the pivot 11 so as to be engaged by the thread as the member 9 is moved to its dotted-line position.

25 What is claimed is:

1. In a tension device for shuttles, a plurality of stationary guide members, and a movable tensioning member cooperating with said guide members and having a channel in which a thread is engaged when threading the device, the movement of said tensioning member being utilized to also engage said thread with said guide members to complete the threading operation.
- 35 2. In a tension device for shuttles, a movable tensioning member formed with a series of loops forming a channel for receiving a thread therein, and a plurality of stationary guide members arranged in the path of movement of said movable member and engaged by the thread extending through said loops so that said thread will extend back and forth between the loops of the tensioning member and said stationary members.

3. In a tension device for shuttles, a pivoted tensioning member having a normal position and formed with a plurality of loops arranged in staggered relation to one another to form a channel for receiving a thread when the device is being threaded, a plurality of stationary guide members having inclined edges and between which portions of said loops pass when the tensioning member is moved about its pivot and which are engaged by the thread in said loop by a movement of said pivoted member so that when the latter is restored to its normal position said thread will extend back and forth between the loops of the pivoted member and said stationary members.

4. In a tension device for shuttles, a movable tensioning member formed from a single length of material bent at one end to provide a coil which forms a pivot for said member and also bent adjacent its other end to provide a plurality of aligned loops for receiving a thread when the device is being threaded, a plurality of stationary guide members capable of being engaged by said thread when said tensioning member is moved about said coil as a pivot so that said thread will be engaged alternately with said loops and said stationary guide members, and means to prevent engagement of said thread with said coil when said tensioning member is moved about its pivot.

5. In a tension device for shuttles, a plurality of stationary guides, a movable tensioning member formed of a single length of wire formed at one end with a helical coil and provided with a plurality of loops arranged in staggered relation to one another to form a channel for the thread, a pin upon which the coil is mounted, and an elastic member secured to the shuttle and to the end of the wire adjacent the coil.

PAUL SHANNON.
